(57) **CLAIM**

The ornamental design for an outlet for a bag able to hold a liquid, as shown and described.

DESCRIPTION

FIG. 1 is a top, front side perspective view of an outlet for a bag able to hold a liquid;

FIG. 2 is a bottom, front side perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a left side elevation view thereof;

FIG. 8 is a right side elevation view thereof; and,

FIG. 9 is a top, front, right side cross-sectional perspective view, taken along line 9-9 of FIG. 2 thereof.

The broken lines are to illustrate the environment only and form no part of the claimed design.

1 Claim, 7 Drawing Sheets
